RADIATOR

Filed June 25, 1919

Fig. 1.

UNITED STATES PATENT OFFICE.

GEORGE A. KILEY, OF LOS ANGELES, CALIFORNIA.

RADIATOR.

Application filed June 25, 1919. Serial No. 306,615.

To all whom it may concern:

Be it known that I, GEORGE A. KILEY, a citizen of the United States, residing at Los Angeles, in the county of Los Angeles and 5 State of California, have invented new and useful Improvements in Radiators, of which the following is a specification.

This invention relates to a radiator and particularly pertains to a radiator of the 10 type employed in connection with internal combustion engines for circulating the water through the engine water jacket and for cooling same.

It is the object of this invention to provide 15 a sectional radiator which embodies a unit adapted to be assembled together with any suitable number of complementary units to form a sectional radiator whereby the size and capacity of the radiator may be varied 20 as occasion may require, and which is so constructed that a unit may be removed for repairs without necessarily putting the other units of the radiator out of operation.

Another object is to provide a radiator 25 unit formed of a series of radiator elements which can be readily removed and replaced for repairs by persons of ordinary skill thus not requiring the employment of experts when repairs are needed and serving with 30 the sectional feature of the radiator to permit removal and repair of damaged units when remote from conveniences and where materials and labor are not available without discontinuing operation of the engine.

Another object is to provide a substantial 35 detachable connection between the adjacent radiator sections which will permit of ready disconnection and reassemblage of the sections and by which a water tight joint will 40 be assured in the connection.

Another object is to provide a radiator 45 unit with a series of flexible zig-zag tubes which will allow for expansion and contraction so as to largely prevent the tubes from being loosened at their connections by this cause.

Another object is to provide means in the 50 radiator for insuring a positive circulation of water therethrough.

A further object is to provide means for 55 manually controlling the flow of water through the radiator from a remote point and for restricting the flow therethrough to quicken warming up of the engine on initial starting thereof.

Other objects will appear hereinafter.

The invention is illustrated in the accompanying drawings, in which;

Figure 1 is a perspective view of a radiator constructed in accordance with this invention with portions broken away to show the internal construction thereof;

Figure 2 is a detail in perspective showing the rear upper portion of the radiator.

Figure 3 is a detail in horizontal section 65 as seen on the line 3—3 of Figure 1.

Figure 4 is a detail in elevation of the nipple for forming communication between adjacent radiator sections;

Figure 5 is a detail in vertical section as 70 seen on the line 5—5 of Figure 4;

Figure 6 is a detail in section illustrating the control valve for regulating the flow of water through the radiator.

More specifically, *a*, *b*, *c*, *d* and *e* indicate 75 separable radiator units, each of which embodies spaced superposed chambers, 7 and 8, which are preferably rectangular in cross section with parallel front and rear walls, 9 and 10; the front walls of the chambers 80

of one unit being adapted to abut against the rear walls of an adjacent unit and substantially conformed thereto. Extended between the superposed chambers is a series of spaced, substantially flat, zig-zag tubes, 85 11, arranged with their narrow edges extending to the front and rear; these tubes having a width nearly corresponding to the width of the superposed chambers. The zig-zag tubes of one radiator unit are positioned 90

to extend opposite the spaces between the tubes on the adjacent unit and the corrugations on one row of tubes are preferably formed to extend in directions opposite the corrugations of the tubes on the adjacent 95

row so as to stagger the tubes in the successive rows relative to each other to form broken or non-continuous air passages between the tubes throughout the depth of the assembled radiator units. By this construction, air flowing through the spaces between the tubes, traverses irregular passages and is 100

brought into intimate contact with the surfaces of the tubes while being thoroughly agitated so as to effect a rapid cooling action.

An important feature of this invention resides in a means for detachably connecting adjacent units and forming communications between the upper chambers and between the lower chambers of contiguous units. This means is particularly shown in Figure 5 and 105

embodies a tube 12, having an out-turned flange 13 on its outer end adapted to seat on and to be secured to an offset flange 14, forming the margin of an opening in one of the 5 walls 9 or 10. The tube 12 extends inwardly to project a short distance into the chamber 7 or 8 and has an inturned flange 15 on its inner end adapted to slidably encircle a tube 16 secured to the inner periphery of a ring 10 17 secured to the offset margin 18 of an opening formed in the opposite wall 9 or 10 and having an annular projection 19 adapted to extend into the tube 12 and to co-operate with the latter in forming a packing gland; 15 a suitable packing material 20 such as mineral washers, encircling the tube 16 at the end of the extension 19 and adapted to seat on the flange 15 to form a water-tight joint when the adjacent walls 9 and 10 are 20 clamped together as will be presently described.

In carrying out my invention, the communication between adjacent chambers 7 is preferably formed intermediate the ends of the chambers as indicated at 21 in Figure 1 and the communication between the adjacent lower chambers 8 is preferably disposed at one end thereof as indicated at 22 in Figure 1 with the communications between the 30 successive units alternating from end to end so that water flowing through the lower chambers 8 will traverse approximately the full length of each chamber. The communications 21 and 22 are preferably oblong in cross-section and the communications 21 are positioned vertically so that the upper ends of the communications will be adjacent to the top wall of the chamber 7 so as to prevent formation of air pockets in the upper 40 portion of the radiators and the communications 22 are positioned to extend horizontally to economize space and yet afford a cross-sectional area substantially corresponding to that of the communication 21. 45 Extending through the chambers 7 and 8 are tubes 23, the ends of which open through the walls 9 and 10 and afford means whereby a series of the radiator units may be secured together by long bolts 24 which extend 50 through alined tubes 23 and engage the outer walls of the end units. These tubes are arranged adjacent each of the communications 21 and 22 preferably at the corners of a rectangle so that when the bolts 24 are tightened, the adjacent radiator units will be 55 drawn into tight contact with each other and with the packing glands around each communication properly united to prevent leakage.

60 As a means of facilitating flow of the water longitudinally of the lower chamber, a baffle plate 25 is disposed in each chamber 8 and extends lengthwise thereof with one end terminating in the end wall and its opposite end spaced from the other end of the

chamber. This baffle plate is arranged to extend above the communication 22 and operates to prevent the direct flow of water from the lower ends of the tubes into the communication 22 and directs the flow of 70 water from each tube to the end of the chamber opposite the communication 22 to the space beneath the baffle.

The forward end unit is fitted with an intake 26 fitted with the usual cap 27 through which intake the radiator may be filled and the rear end unit has a tubular connection 28 for forming communication with the water jacket of an internal combustion engine in the usual manner; the rear unit being also fitted with an outflow conduit 29 leading to the lower portion of the engine water jacket, as is common in radiator construction. As a means for restricting the flow of water through the radiator and water jacket, as on initial starting of the engine, to hasten preheating thereof, a butterfly valve 30 is mounted in the conduit 29 and has a stem 31 extending through a packing gland 32 on the conduit 29. The outer end of the stem 31 is connected by a universal joint 33 to a turnable rod 34 extending to a point convenient to the reach of the driver and the rod 34 is fitted with an operating lever 35 adapted to be engaged by a notched segment 36 by which the lever 35 may be held in various positions to retain the valve 30 in any desired adjusted position. As a means for preventing complete cutting off of the flow of water through the radiator, valve 30 is formed with a cut-away portion 37 which, when the valve is closed, forms an opening through which a limited amount of water may pass.

In the construction and assemblage of the radiator, a unit may be formed with any desired number of tubes and any desired number of the units may be assembled together according to the area of radiating surface desired.

In event either of the units become damaged or leak from any cause, they may be removed and replaced by other units pending repairs. By forming the radiating surfaces of the zig-zag or corrugated tubes and forming the connection between the tubes and the walls of the chambers 7 and 8 by soldered joints, these tubes may be readily removed and replaced by persons of ordinary skill.

Whilst I have shown and described a specific embodiment of my invention, it is obvious that various changes may be made in the details of construction and the arrangement of parts as may be necessary under varying conditions without departing from the spirit and scope of the invention as set forth in the appended claim.

I claim:

In a radiator, a series of detachably con-

nected units each of which embodies a pair of spaced superposed chambers and a series of zig-zag flexible tubes connecting said chambers, the adjacent zig-zag tubes on a unit being parallel to each other with the series of tubes on one unit arranged with their inclined portions extending diagonally

to the inclined portions of the tubes on the adjacent unit, the adjacent upper chambers being in communication intermediate their ends and the adjacent lower chambers being in communication adjacent to one of their ends. ¹⁰

GEORGE A. KILEY.
